UNITED STATES PATENT OFFICE.

CHARLES W. DAKE AND JOHN E. KILKER, OF CHICAGO, ILLINOIS, ASSIGNEES TO PYLE NATIONAL ELECTRIC HEADLIGHT COMPANY, OF CHICAGO, ILLINOIS, A CORPORATION OF NEW JERSEY.

DESIGN FOR A CASING FOR MOTORS AND GENERATORS.

42,316.

Specification for Design.

Patented Mar. 19, 1912.

Application filed October 12, 1911. Serial No. 654,409. Term of patent 14 years.

To all whom it may concern:

Be it known that we, CHARLES W. DAKE and JOHN E. KILKER, citizens of the United States, residing at Chicago, in the county of Cook and State of Illinois, have invented a new, original, and ornamental Design for a Casing for Motors and Generators, of which the following is a specification, reference being had to the accompanying drawing, forming part thereof.

The figure is a perspective view of casing

for motor and generator showing our new design.

We claim:

The ornamental design for a casing for a motor and generator as shown.

CHARLES W. DAKE.
JOHN E. KILKER.
